UNITED STATES PATENT OFFICE.

LOUIS J. LARSEN, OF LONG ISLAND CITY, NEW YORK.

MOUNTING FOR BOOMS AND SAILS.

Application filed February 5, 1927. Serial No. 166,055.

This invention relates to improvements in rigging for sail-boats, and has particular reference to a mounting for booms and sails.

It is customary in connection with the sailing of boats, and more especially yachts used for pleasure and racing purposes, to include in the equipment thereof more than one sail of a particular type. This is done in order that the kind of sail is available which is most suitable for the prevailing weather or wind. For example, when there is a strong wind blowing it is desirable that the sail used be of a flat type, that is, one which will have only a slight curvature when filled, whereas in a light wind it is usual to employ a sail the curvature or draught of which, when filled, is greater than that of the so-called flat sail.

Also, the connections, which are at present being used to join the lower end of the fore edge of a mainsail to the mast, are such that it is very difficult at times to maintain the full length of said fore edge in parallel relation to the mast.

An object of the present invention is to provide a mounting of simple and practical construction by means of which a sail may be adjusted relative to its mast and boom to vary the curvature of the sail, when filled, thereby avoiding the necessity of changing from one sail to another to meet existing weather conditions.

Another object is in providing an adjustment for the sail whereby the fore edge and foot or lower edge thereof throughout their entire lengths may be kept in parallel relation to the mast and boom, respectively, thus insuring the proper positioning of the sail under all conditions.

A further object is the provision of an improved mounting which will allow of free swinging movements of the boom both vertically and laterally relative to the mast.

The above and other objects will appear more clearly from the following detail description, when taken in connection with the accompanying drawing, which illustrates a preferred embodiment of the inventive idea.

In the drawing—

Figure 1 is a side elevation of the mounting constructed in accordance with the invention and shown in its operative position;

Figure 2 is a top plan view of the mounting with the sail unattached; and

Figure 3 is a section on the line 3—3 of Figure 1.

Referring more particularly to the accompanying drawing, the numeral 4 indicates the mast of a sailing boat and 5 the usual boom to which the mainsail 6 is connected. 60

The mounting of the present invention consists of a bracket 7 secured to the mast 4 and having a bearing portion 8 provided with an opening 9 therethrough, which opening is disposed co-extensively with the mast. 65 A supporting member 10, in the form of an arm, is provided at one end with a lateral extension 11 which is mounted in the opening 9 so as to form a pivot for the member 10 to permit of the same to be swung about 70 a vertical axis and laterally with respect to the mast 4. The other end of the support 10 is also provided with a lateral extension 12 terminating at its extremity in an eye 13 through which is extended a pin 14 in the 75 form of a bolt, the eye being engaged with the intermediate portion of said pin. To connect the boom 5 with the pin in order that the former may have vertical movements about said pin as a pivot, there is 80 provided a yoke 15 having a screw threaded shank 16 which is screwed into the end of the boom 5, as shown in Figure 1. Thus from the foregoing description it will be 85 apparent that through the pivotal connection of the support 10 with the mast and the similar connection of the boom with said support, said boom will have pivotal movements both laterally and vertically relative to said mast. 90

The mounting further comprises a means for adjustably securing the sail 6 thereto, said means consisting of the opposed clamping plates 17, adjacent ends of which are provided with openings for receiving the pin 95

14 with the plates arranged on opposite sides of the eye 13 and between the same and the arms of the yoke 15. The opposite ends of said plates are likewise provided with openings for receiving a pin 18 similar to the pin 14, which pin 18 also extends through an eye 19 formed upon the extremity of the extension 11. The plates 17 are capable of movements toward and away from each other on the pins 14 and 18 so as to be capable of clamping therebetween the end 20 of a sail attaching member 21. The inner surfaces of the plates and the surfaces of said end 20 are milled or serrated so that when the clamping plates are engaged with 105 said end the same will be securely held together after the wing nut 22 has been 110

threaded upon the bolt 23 and engaged with the adjacent plate 17, said bolt projecting through slots 24 and 25 extending, respectively, longitudinally of the plates 17 and end 20. The slots 24 provide a means whereby the attaching member 21 may be adjusted longitudinally of said plates to permit of variations being made in the curvature of the sail 6. The slot 20 permits of a transverse adjustment of the member 21 relative to said plates whereby the foot or lower edge of the sail 6, and particularly the fore part thereof, may be caused to extend co-extensively with the boom 5.

15 The intermediate portion of the attaching member 21 is disposed transversely to the end 20 and has extending therefrom in a direction opposite to the end 20 an offset end 26 terminating at its extremity in the yoke 27 between the arms of which is adapted to be disposed the adjacent corner of the sail 6. In order to connect said sail to the yoke the arms of the latter are provided with opposed openings 28 into one of which projects a pin 29. A locking bolt 30 is extended through the openings 28 and has therein a bayonet slot 31 in which is engageable the end of the pin 29. The bolt is provided with a head 32 which is capable of being given a quarter turn so that the pin 29 will engage in the longitudinal portion of the slot 31 and thus permit of a partial withdrawal of the bolt from the yoke, thereby allowing of the insertion of the corner of the sail between the arms of said yoke. The bolt is then replaced to its locking position, extending through an eye 33 formed in the sail so that the sail will be attached to the member 21. In order to insure the locking bolt remaining in its locking position with the head 32 extending downwardly, a short length of rope (not shown) may be tied to the head through an opening 34 therein and also to a stationary part of the boat. By thus attaching the sail it will be apparent that the entire length of the fore edge, and particularly the lower end thereof, can be at all times maintained in parallel relation with the mast 4 when the member 21 is in the position shown in Figure 1. It is also obvious that said member 21 may be adjusted longitudinally of the plates 17 and away from the mast 4 to vary, within certain limits, the curvature which the sail 6 will assume when it is filled.

40 If desired, there may be interposed between the top of the bearing 8 and the lower edges of the plates 17 a split washer 35 which encircles the extension 11 to take up wear between the parts.

45 What is claimed is:

1. A mounting for booms and sails including a supporting member capable of attachment to a mast for swinging movement about an axis parallel thereto, opposed clamping

plates carried by said supporting member and movable toward and away from each other, means for pivotally connecting a boom to said supporting member for movement in a vertical direction, and a sail attaching member held between said plates and having longitudinal and transverse adjustments relative thereto.

2. A mounting for booms and sails including a supporting member capable of attachment to a mast for swinging movement about an axis parallel thereto, opposed clamping plates carried by said supporting member and having longitudinal slots therein, means for pivotally connecting a boom to said supporting member for movement in a vertical direction, a sail attaching member held between said plates and having slots therein which extend transversely of and intersect the slots in said clamping plates, and means extending through the slots in said plates and sail attaching member for securing the latter in different adjusted positions longitudinally and transversely of said plates.

3. A mounting for booms and sails including a supporting member capable of attachment to a mast for swinging movement about an axis parallel thereto, opposed clamping plates carried by said supporting member and movable toward and away from each other, means for pivotally connecting a boom to said supporting member for movement in a vertical direction, a sail attaching member having one end thereof disposed between said clamping plates and its other end bifurcated to receive a portion of a sail therebetween, and a locking device mounted in said bifurcated end and engageable with said sail to releasably connect the same to said attaching member.

4. A mounting for booms and sails including a supporting member capable of attachment to a mast for swinging movement about an axis parallel thereto, opposed clamping plates carried by said supporting member and movable toward and away from each other, means for pivotally connecting a boom to said supporting member for movement in a vertical direction, a sail attaching member having one end thereof disposed between said clamping plates and its other end bifurcated to receive a portion of a sail therebetween, a locking device mounted in said bifurcated end and engageable with said sail to releasably connect the same to said attaching member, and means for adjusting said attaching member both longitudinally and transversely of said clamping plates.

5. A mounting for booms and sails, including a supporting member having a lateral extension at one end forming a pivot for the member capable of attachment to a mast to permit said member to swing laterally relative thereto, said supporting member having another lateral extension at its other end,

connecting pins mounted transversely in the extensions of said member, clamping plates carried by said pins and movable thereon toward and away from each other, means
5 joined to one of said pins for pivotally connecting a boom thereto for vertical movements, and a sail attaching member held between said plates and having longitudinal and transverse adjustments relative thereto.
10 6. A mounting for booms and sails including a supporting member having a lateral extension at one end forming a pivot for the member capable of attachment to a mast to permit said member to swing laterally relative to the mast, said member having another lateral extension at its other end, connecting

pins mounted transversely in the extensions of said member, clamping plates carried by said pins and movable thereon toward and away from each other, said plates having 20 longitudinal slots therein, means for pivotally connecting a boom to one of said pins for vertical movements, a sail attaching member held between said plates and having slots therein which intersect the slots in said 25 clamping plates, and means extending through slots in said plates and sail attaching member and engageable with said plates to secure the sail attaching member thereto.

In testimony whereof I have affixed my 30
signature.

LOUIS J. LARSEN.
